UNITED STATES PATENT OFFICE.

NORMAN M. SMALL, OF WAYNESBORO, PENNSYLVANIA, ASSIGNOR TO FRICK COMPANY, OF WAYNESBORO, PENNSYLVANIA, A CORPORATION OF PENNSYLVANIA.

AIR-AGITATING-TUBE SUPPORT FOR ICE MACHINES.

Application filed March 4, 1927. Serial No. 172,747.

My said invention relates to ice making machines in which freezing cans are supported in a grid or framework, such freezing cans being supplied through tubes with air for agitating the water to be frozen in the cans. As commonly constructed the tubes for supplying air for agitating water are supported by means of brackets removably attached to the sides of the cans and when the ice is removed it is first necessary to remove the brackets to permit the ice to be discharged from the cans.

The object of my invention is to provide a bracket which may be swung out of the way when the ice cake is being removed from the can and one to which the tube may be readily attached and detached and at the same time be supported to swing as desired to secure the best results, thus facilitating and simplifying the operation, all as will be hereinafter more fully described and claimed.

Referring to the accompanying drawings, which are made a part hereof and on which similar reference characters indicate similar parts,

Figure 1 is a top plan view of one form of hinge bracket illustrating the application of my invention,

Figure 2, a side elevation,

Figure 3, an end elevation,

Figure 4, a top plan view of a modified form of bracket,

Figure 5, a side elevation,

Figure 6, a top plan view of another modified form,

Figure 7, a side elevation,

Figure 8, an end elevation,

Figure 9, a top plan view of another modified form bracket,

Figure 10, a side elevation,

Figure 11, a detail fragmentary perspective,

Figure 12, a top plan view of another form of bracket,

Figure 13, a side elevation,

Figure 14, a side elevation of a modified type of tube head,

Figure 15, a front elevation of a device for lifting air tubes from the cans, and

Figure 16, a side elevation.

In the drawings, reference character 10

indicates the upper portion of an ice can about the upper rim of which is secured a band 11 for reenforcing the edge and to which rim is secured in any desired manner, as for example by rivets 12, a hinge part 13 to which a part 14 is hinged and forms a bracket for supporting an air agitating tube 15 which is detachably connected to the end thereof. The hinge is mounted in such position relative to the top of the can and reenforcing band that its 55 swinging portion will rest on and be supported by the same when in a horizontal position. The free end of the bracket 14 is bifurcated to permit the head 16 of the tube 15 to be disposed therein. The arms are curved at 60 17 to form depressions in which rest transversely extending ends of a supporting pin 18. In order to maintain the supporting pin 18 in the proper position, a bifurcated spring plate 19 is secured by means of rivets or the 65 like to the bracket 14 and the forward ends of the spring plate and bracket are curved oppositely outwardly in order that they may be forced apart by the supporting pin 18 when it is forced into position.

In lieu of the type of hinge shown in Figures 1 and 2 a hinge such as shown in Figures 4 and 5 may be used such hinge comprising a section 20 secured by means of rivets 21 to the can rim, such section having formed at its 70 upper end spaced pintle eyes 22 in which is supported a pin 23 upon which is pivoted a bracket 24 having a pintle eye 25 disposed between the pintle eyes 22 on the pin 23. The pintle eyes 22 are provided with slots 27 in 75 which are disposed the laterally extending ears 28 which contact with the ends of the slot and form steps by means of which the bracket 24 is prevented from moving below a horizontal position.

Instead of the air tube being supported in the manner shown in Figures 1 to 5 it may be supported in the manner shown in Figures 6 to 8 wherein the head 30 is provided with a supporting pin 31. The bracket 29 is bifurcated like the bracket shown in the preceding figure. The parts of the bracket at the sides of the bifurcation are bent around and form pintle eyes 32 for the pin. Mounted in the head 30 is a short section of tubing 33 having 100

a slightly flared upper end 34 provided with grooves or slots disposed in parallel relation to the pin 31 for receiving the supporting pins 36 of an agitator tube 35.

- 5 In lieu of the manner of supporting the agitator tube shown in preceding figures the tube may be supported as shown in Figures 9 to 11 in which a bracket 37 is provided with an opening 38 between its mountable end and a tongue 39 is also provided at its extremity. A detachable section 40 is provided for engagement with the end of the bracket 37, said detachable section having a rearwardly extending tongue 41 with an upstanding portion 42 designed to fit into the opening 38, said detachable section being provided with brackets 43 which extend upwardly and rearwardly in parallel relation with the bracket 41, such brackets being spaced at the opposite side of the body and arranged to receive the tongue 39 between the same and extend over the portion of the bracket at the sides of the tongue to form a firm connection therewith. The detachable bracket section 40 is bifurcated at its forward end and pintle eyes 44 are formed at each side of the bifurcation for engagement with the supporting pin 45 of an agitating tube 46.

With the types of brackets shown in the foregoing figures the air agitating tubes are supported to swing in a single plane and longitudinally of the supporting bracket, or cross-wise the can. When desired to have the agitating tube swung in all directions, or be universally mounted, a modification such as shown in Figures 12 and 13 may be employed. In this form a bracket 47 is provided with an aperture 48 adjacent its forward end which aperture may be tapered to conform to the head 49 of an air agitating tube 50, such head being preferably spherical and rests in the tapered aperture, permitting a universal movement of the tube. By providing the agitating tube 51 with a square head 52, as shown in Figure 14 the tube would be held stationary, when such result is desired.

It will be understood that the bracket shown attached to a freezing can may as readily be attached to the grid, can basket, or the framework used in connection with the loose can system of manufacturing ice, with the resulting well understood advantages, and that such attachments, or either of them, are contemplated by the language of the claims. The bracket is herein shown and described as attached at the long side of the can and swings across the narrow dimension thereof. It will be understood that while this arrangement is preferable the attachment may be so made as to require the tube to swing the long dimension of the can without departing from the spirit of my invention.

A body member or support 53 is provided in which is mounted a coupling member 54 for

connection with a hot water or steam pipe to which is secured a depending tube 55 for conducting hot water or steam into the air tube for thawing the same loose from the ice when it is desired to remove the same after the cake is frozen. A pair of hooks 56 joined by a strap 57, which may be formed integrally therewith, are supported on pivot screws 58. By means of the hooks 56 the air tube may be withdrawn by engaging the hooks under the supporting pins for the air tube.

While the tube lifter is not absolutely essential, the tubes being readily removable by hand, nevertheless it has been found of advantage.

In the operation of freezing ice the generally approved method recognizes that the best results are secured by so supporting the air agitating tube that it will swing in a single plane across the can and preferably across the short dimension or diameter of the can. While I have shown numerous forms of tube supports, each adapted to serve the fundamental purpose of the invention, i. e., to permit the supporting bracket to be swung out of the way during the operation of "harvesting" the ice and at the same time provide a support of a permanent character in a fixed position with the consequent advantages, yet it will be understood that many other schemes to accomplish the same end may be devised. Several different forms of devices are also illustrated for attaching the agitating tube to the bracket in a manner that will permit its ready attachment and detachment and at the same time hold the tube so that it will swing or oscillate during the freezing operation in a transverse direction across the can and be restrained from movement in other directions. It will be obvious to those skilled in the art that various other changes may be made in the construction and arrangement without departing from the spirit of my invention and therefore I do not limit myself to what is shown in the drawings and described in the specification but only as indicated in the appended claims.

Having thus fully described my said invention, what I claim as new and desire to secure by Letters Patent, is:

1. The combination with an ice can for containing water to be frozen and a tube for supplying air for agitating the water during the freezing operation, of a bracket for supporting said tube, said bracket being permanently hinged to the can at one side thereof and being swingable to a position out of the path of the ice being discharged from said can, and means at the free end of the bracket for detachably supporting said air tube, substantially as set forth.

2. The combination with an ice can for containing water to be frozen and a tube for supplying air for agitating the water during the

freezing operation, of a bracket for supporting said tube, said bracket being permanently hinged to the can at one side thereof and being swingable to a position out of the path of the ice being discharged from said can, said bracket having a perforation formed at its free end and yieldable means for detachably

maintaining said air tube in said perforation, substantially as set forth.

In witness whereof, I have hereunto set my hand at Waynesboro, Pennsylvania, this 25th day of February, A. D. nineteen hundred and twenty-seven.

NORMAN M. SMALL.
